UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

LOOM-SHUTTLE.

1,091,867.

Specification of Letters Patent. Patented Mar. 31, 1914.

Application filed December 3, 1909. Serial No. 531,172.

To all whom it may concern:

Be it known that I, EDWARD S. STIMPSON, of Hopedale, in the county of Worcester and State of Massachusetts, have invented 5 certain new and useful Improvements in Loom-Shuttles, of which the following is a specification.

The present invention consists in improvements in connection with the automatically threading devices at the eye end 10 of the shuttle; and in connection with the means employed for supplying friction to the yarn as it is delivered from the shuttle. These improvements are illustrated in the 15 accompanying drawings, wherein:—

Figure 1, is a plan view of the eye end of a shuttle equipped with the improvements. Fig. 2, is a perspective view of a spacer used at the eye end of the shuttle. 20 Fig. 3, is a vertical longitudinal section in the plane indicated by the line 3—3 in Fig. 1. Fig. 4, is a cross section in the plane indicated by the line 4—4 in Fig. 3.

At its eye end the shuttle is provided with 25 a single piece sheet metal threading device made in accordance with the United States Letters Patent to myself, No. 933,497, September 7, 1909. As in said patent this single piece sheet metal threading device is 30 formed with two parallel side walls J, J, connected at their lower edges by a flat bottom K. The space between these side walls J, J, is open at the top and both ends and constitutes a thread passage for the yarn 35 passing from the weft-carrier to the eye of the shuttle located at L. Also, as in said patent, the bottom of the threading device has an upwardly and forwardly turned ear M, at its rear end, shown in Fig. 4. This 40 sheet metal threading device is located within a recess at the forward end of the shuttle body A and is held in place by means of a bolt N, and a nut O, the bolt passing through holes in the side walls J, J, of the 45 threading device. A difficulty is encountered with such a sheet metal threading device, namely, the screwing of the bolt N, into place may tend to force the walls J, J, toward each other and thus interfere with 50 the action of the thread directing instrumentalities which are formed in one piece of sheet metal with the said side walls. To prevent this, the spacer P, is employed. This spacer is shown separately in Fig. 2, 55 and it is simply a small metal plate with

parallel sides and with its ends bent to form downwardly diverging legs d. The width of the spacer is equal to the space between the side walls J, J, so that when the spacer is fitted into place, as shown in Figs. 60 3 and 4, it keeps the walls J, J, apart against any pressure of the holding bolt N. As shown in Fig. 3, the spacer P, just fits between the upwardly and forwardly turned ear M, and the bolt N. Consequently, the spacer is securely held in place with no danger of getting out. This spacer P, occupies the position in the improved shuttle which was occupied by the friction pad of the said Patent No. 933,497. Accordingly, 65 the present improvements provide a novel arrangement of friction pad. In the present case the bottom K, of the threading device has a hole e, near its front end which registers with a hole f, in the 70 bottom wall of the shuttle body. The friction pad Q, is constituted by a bundle of threads which are drawn through and securely held in the holes e, and f, and are flush with the under side of the shuttle 75 body. The upper ends of this group of threads remain as a tuft extending upwardly into the thread passage between the side walls J, J, and forward of the retaining bolt N. The upper ends of this tuft 80 of threads are in the path of the thread on its way from the weft-carrier to the shuttle eye and it imparts sufficient friction to the 85 thread.

The hole e, in the bottom K, of the threading device is less in diameter than the registering hole f, in the bottom of the shuttle, as shown in Fig. 3. The bundle Q, of threads is squeezed together in drawing through the hole e, and expands within the 90 hole f, and above the plate K, so that the bundle is efficiently and securely held in place by this expedient alone. The two holes e, and f, can be regarded as a single 95 hole, in which event the hole is restricted in diameter at the portion e, thereof whereby the bunch or tuft Q, is squeezed or compressed at this place and expands both 100 above and below this restriction.

I claim—

1. A loom shuttle having, in combination, a one piece sheet metal threading device having parallel side walls and a uniting bottom, a thread passage open at the top and at both ends being provided above said 110

bottom and between said side walls; an upwardly and forwardly bent ear in one with and at the rear of said bottom; a retaining bolt passing through the body of the shuttle and through said side walls; and a spacer fitting in the space between said side walls, and having diverging legs, the forward leg being adjacent said retaining bolt and the rear leg being adjacent said upwardly and 10 forwardly turned ear.

2. A loom shuttle having, in combination, a metal threading device having a thread passage between its side walls and above its bottom; and a friction pad consisting of a 15 bunch or tuft of threads passing through

and held in a hole in the bottom of the threading device and the lower end of said bunch or tuft extending into a larger hole in the bottom of the shuttle below said hole in the bottom of the threading device, this 20 constituting the sole means for retaining the said bunch or tuft in place.

In witness whereof, I have hereunto signed my name in the presence of two subscribing witnesses.

EDWARD S. STIMPSON.
